UNITED STATES PATENT OFFICE.

ARTHUR E. ANAKIN, OF LONG BEACH, CALIFORNIA.

SPRING-OPERATED TUMBLER LOCK.

Application filed January 6, 1925. Serial No. 760.

This invention relates to improvements in locks.

It is an object of the invention to provide an improved lock having tumblers, in which means is provided whereby when one of the tumblers is lifted into open or unlocking position, a corresponding tumbler will be urged thereby into locking position. By this construction it is desired to provide a lock which cannot be "picked".

With the foregoing and other objects in view which will be made manifest in the following detailed description and pointed out in the appended claims, reference is had to the accompanying drawings for an illustrative embodiment of the invention, wherein:—

Figure 1 is a vertical section through the improved lock;

Fig. 2 is a vertical section taken substantially on the line 2—2 of Fig. 1;

Fig. 3 is a side elevation of the improved lock; and

Fig. 4 is a detail of one of the lower tumblers of the lock.

Referring to the accompanying drawings wherein similar reference characters designate similar parts throughout, the improved lock consists of a body 10, which may be hollow as indicated at 11, or of any other suitable structure. A cylindrical opening 12 is formed in the body 10 in which there is rotatably mounted a cylinder 13. The cylinder 13 has a keyway or key passage 14 formed therein adapted to receive a key K. A suitable lever 15 is mounted upon the rear of the cylinder 13 as by screws 16, which lever is operatively connected with a latch or bolt 17 so that when the cylinder 13 is rotated, the latch or bolt may be thrown into locking or unlocking position. Tumbler slots 18 are formed in the cylinder 13 and these tumbler slots communicate with the keyway 14. Additional tumbler slots 19 are formed in the body 10 and are adapted to register with the tumbler slots 18. Preferably when the body 10 is hollow, suitable bosses 20 are formed about the tumbler slots 19 to provide additional bearing surface for the upper tumblers 21. Lower tumblers 22 are disposed within the tumbler slots 18 and the upper and lower tumblers are adapted to slide within the tumbler slots upon engagement with the key K to assume unlock position, as shown in Fig. 1.

A feature of the invention resides in pro-

viding means whereby when one of the tumblers or sets of tumblers is raised to unlocking position, a corresponding tumbler is resiliently or yieldably urged into locking position so as to prevent "picking" of the lock by raising some of the tumblers by an instrument other than the proper key.

The upper tumblers 21 are provided with grooves or slots 23 which grooves receive the ends of springs 24. Suitable apertures 25 are formed in the body 10 and extend transversely thereacross. Pins 26 are secured within these apertures and the springs 24 constituting resilient levers are pivoted upon the pins 26. In the preferred form of construction, the springs 24 engage alternate tumblers, although it is to be considered within the scope of this invention to so arrange the springs 24 that they may engage upon adjacent tumblers. If the lower and upper tumblers adjacent the front of the lock are lifted by an instrument inserted in the keyway 14 other than the key K, the upper and lower tumblers which are third from the front of the lock will be urged downwardly or into locking position. It will, therefore, be readily understood that in order to unlock the lock, it is necessary that all of the tumblers be lifted the proper distance against the action of the springs 24 and that this can only be accomplished by inserting the proper key K. The tumblers may be inserted into the lock through suitable openings 27, which may be afterwards closed, if desired.

Another feature of this invention resides in mounting balls 28 within the body of each of the lowermost tumblers 22. The balls 28 are held within the tumblers and are rotatable therein. The object of the balls 28 is to decrease the friction upon inserting the key K; it being understood that if the balls 28 were not present, the friction in the improved lock would be considerably greater due to the action of the springs 24 than if the tumblers fell under the force of gravity.

It is to be understood that various changes in the detail of construction may be made without departing from the spirit or scope of the invention as defined by the appended claims.

I claim:—

1. A lock comprising a body, a cylinder rotatable in said body, a keyway formed in said cylinder, tumbler slots formed in said cylinder and in said body one behind the

other along the keyway, upper and lower tumblers slideable in said tumbler slots, and springs pivoted within said body, each spring engaging alternate tumblers.

5. 2. A lock comprising a body, a cylinder rotatable in said body, a keyway formed in said cylinder, tumbler slots formed in said cylinder and in said body one rearwardly of another along the keyway, upper and lower tumblers slideable in said tumbler slots, springs pivoted within said body, each spring engaging alternate tumblers, and grooves formed in said upper tumblers adapted to receive the ends of said springs.
10. 3. A lock comprising a body, a cylinder rotatable in said body, tumbler slots formed in said body and cylinder in longitudinal alignment, tumblers disposed within said slots, a key receivable within said cylinder for moving said tumblers into such position as to permit rotation of said cylinder within the body, and a pivoted resilient lever mounted within said body having its ends engaging separate tumblers and urging them into locking position.
15. 4. A lock comprising a body, a member

movably mounted in said body, tumbler slots formed in said body and member, one behind the other longitudinally of said member, tumblers within said slots, a key receivable in said member for moving the tumblers into unlocking position, whereby said member may be moved within said body, and a pivoted resilient lever disposed within said body engageable upon two of the tumblers urging them into locking position.

5. A lock comprising a body, a member movably mounted in said body, tumbler slots formed in said body and member, one behind the other longitudinally of said member, tumblers within said slots, a key receivable in said member for moving the tumblers into unlocking position, whereby said member may be moved within said body, and a pivoted resilient lever disposed with- in said body engageable upon two of the tumblers, between which a third tumbler is positioned, urging them into locking position.

In testimony whereof I have signed my name to this specification.

ARTHUR E. ANAKIN.
